UNITED STATES PATENT OFFICE

113,345

DESIGN FOR A MOTOR VEHICLE

Meril L. Eckman, Cleveland, Ohio, assignor to
The American Coach & Body Company, Cleveland, Ohio, a corporation of Ohio

Application December 12, 1938, Serial No. 81,729

Term of patent 14 years

To whom it may concern:

Be it known that I, Meril L. Eckman, a citizen of the United States, residing at Cleveland, in the county of Cuyahoga and State of Ohio, have invented a new, original, and ornamental Design for a Motor Vehicle, of which the following is a specification, reference being had to the accompanying drawings, forming a part thereof.

In the drawings, Fig. 1 is a perspective view of a motor vehicle embodying my design; Fig. 2 is a rear view of the vehicle; Fig. 3 is a side elevation illustrating the side opposite that shown in Fig. 1. The dominant features of my design reside in the portions shown in full lines.

I claim:—

The ornamental design for a motor vehicle, substantially as shown and described.

MERIL L. ECKMAN.
